UNITED STATES PATENT OFFICE.

FRANCIS E. BEESON, OF TOPEKA, KANSAS.

GRAIN-DISPENSING VALVE.

Application filed January 27, 1925. Serial No. 5,086.

To all whom it may concern:

Be it known that I, FRANCIS E. BEESON, a citizen of the United States, residing in Topeka, county of Shawnee, and State of Kansas, have invented certain new and useful Improvements in Grain-Dispensing Valves, of which the following is a specification, reference being had to the accompanying drawings, which form a part of this application.

My invention relates to a valve for dispensing grain from a box car, the objects of my invention are as follows.

First—To provide a valve to be placed in the floor of an ordinary box car in which small grain such as wheat, oats, barley etc. are shipped.

Another object of my invention is to provide a mechanism functioning as a valve, and made in one unit so that by removing or omitting a section of the floor, the device can be inserted, being flush with the floor level.

A still further object of my invention is to provide a floor valve for dispensing grain having safety means to prevent opening until the seal of the outside door has been broken, and the door opened in the regular way.

A still further object of my invention is to provide a valve that will not permit the door of the car to be closed until the valve is properly closed and locked, these and other objects will be herein more fully explained.

In the drawings like numerals will refer to like parts in the various views.

Fig. 1 is a side elevation of a fragmentary part of a box car such as commonly used for transporting grain.

Fig. 2 is a diagrammatical plan of the floor of a box car illustrating position of valves.

Figs. 3, 4, and 5 are details of the valve, parts being removed for convenience of illustration.

Fig. 6 is a view showing a possible action of the locking lever.

In Fig. 1, is illustrated a car positioned over a grain pit in connection with a grain elevator, the valve being removed allowing the grain to discharge into the pit.

In Fig. 2, 1 is the floor of the car, 2 is a door being closed, 2' is a door standing open, 3 shows the position of a valve relative to the door post A, allowing the valve

to be positioned to one side of the principal travel into and out of the car, when the car is being used for other merchandise that would require trucking etc. The valve B' on the opposite side of the car is positioned in like manner relative to the door opening, and the valve thereof being partly open.

In Fig. 2 it will be readily seen that the valves must be closed before the doors of the car can be closed, and likewise impossible to open the valves until the car doors have been opened.

Referring to my valve mechanism in detail, 4 is a frame being ship lapped as at B, so that the said frame will match with the floor boards which are matched to coincide therewith. This arrangement is convenient in applying the mechanism when the car floor is being laid, or on removal of an old floor for the valve installation. The valve 5 is slidably engaged in said frame the said valve having a tongue as at C, engaging in the groove of the side members of said frame, and the said side frame having a tongue D, engaging in a groove in the sides of said valve, this tongue being bevelled as shown, and the adjacent wall of the groove conforming thereto. The object of this is to have a close engaging joint adapted to close under the weight of the grain, and continuous wearing will cause the said members to more closely engage.

At the end of the valve as at E, the joint is ship lapped, being so arranged that by reason of wear of the locking members should the valve at this joint be slightly open, the grain cannot pass through. On the opposite end of said valve is a locking device comprising a lever 6, and bolts 7, said lever being pivoted at 8, and the said bolts pivotally connected to said lever at 9, the bolts being adapted to engage in apertures 10, the bolts being actuated by the rocking motion of lever 6 as shown by dotted line F, causing said bolts to engage or disengage with said apertures.

The said lever 6 also functions as a handle when rocked outward at which time the bolts 7 disengage, allowing the valve to be opened as shown by dotted lines G, in Fig. 5. On the opposite end of said valve is a pivotally mounted stop 11, said stop adapted to engage on the car sill as at 12, and the said stop is adapted to rock sidewise, suffi-

cient to pass over the top of the sill allowing the valve to be removed from its frame. Should the valve be closed without engaging the lock, note the door can not be closed 5 the condition being illustrated in Fig. 4, 13 being the door. The end of the lever 6 being bevelled as at H, functions for two purposes, first, providing a thin edge so that the finger or a bar will easily engage 10 on the back thereof, for pulling the lever outward, second to function as a spur, that when being out sufficient for the door to pass over, the spur will cut into the back of the door, so that it cannot be further 15 closed, this being a safety means to insure a careful locking of the valve.

It will be understood that when the car is loaded with wheat or other grain the door of the car will be closed and sealed, 20 and as the door covers the end of the valve it will be impossible to cause an opening of the valve until the car reaches its destination, and is legally opened by the party to whom it is consigned.

25 I have provided two valves for each car, one being on each side and in close proximity to the door post, this will accommodate for unloading the car from either side.

It will be understood that by my valve 30 unloading method, the grain will first be removed from the grain doors, this makes it possible to remove the said doors so as to preserve them for further use which is a great saving to the railroad company, 35 and also a saving in time and labor for the consignee.

I do not confine myself to any particular kind of materials to be used in the construction of my valve but would recommend that it be made of steel, nor do I 40 confine its use to box cars only, as the same may be applied to other grain containers, in transit or stationary, such modifications may be employed as lies within the scope 45 of the appended claims. Having thus described my invention what I claim as new and desire to secure by Letters Patent is:

1. In a grain dispensing device, a valve comprising a frame having a slidably 50 mounted member therein, a lock for said

valve, an actuating lever for said lock, said lever functioning as means for opening said valve for the purpose set forth and described.

2. In a grain dispensing device, a frame 55 positioned in the floor of a grain container, said frame having perforations in the outer ends thereof, a valve slidably mounted in said frame, reciprocating bolts slidably mounted in the outer end of said valve, a 60 lever actuating said bolts simultaneously for engagement with said perforations, said lever functioning as a handle to withdraw said valve.

3. In a grain dispensing device, a frame, 65 rabbets on the sides of said frame, said rabbets adapted to conform to the rabbets of the floor boards for convenience of installation, a groove on the inside edges of said frame, said groove being on the opposite edge from said rabbet, perforations in the outer ends of said frame, a valve slidably engaging in said frame, tongues on the sides of said valve said tongues engaging 70 in the said grooves of said frame, perforations in the outer end of said valve, said perforations adapted to register with the perforations in the outer ends of said frame, a slot in the outer end of said valve, a lever pivotedly mounted in said slot, bolts 75 connected to said lever, said bolts engaging through the perforations in said valve and adapted to engage in the perforations in the outer ends of said frame functioning as a lock, the said lever functioning as reciprocating means for said bolts, and as means for unlocking and withdrawing the valve 80 simultaneously, also as a door stop, until said valve has been locked substantially as shown and described.

4. In a grain dispensing device, in combination with a grain car, a frame set flush with the floor of said car, a valve slidably mounted in said frame, a lock and a lever attached to said valve, said lever extending 85 outward functioning as a stop for the door of the car when the lock is disengaged, all for the purpose described.

FRANCIS E. BEESON.
